E. L. Mustee & Sons, Inc.

Filed Feb. 27, 1963, Ser. No. 73,742

Term of patent 14 years

(Cl. D4—2)

Fig. 1

The side opposite to that shown in FIG. 1 is a mirror image thereof and the rear is plain. The dominant features of my design reside in the portions shown in full lines.

I claim:

The ornamental design for a double laundry tub and cabinet combination, as shown and described.
